UNITED STATES PATENT OFFICE.

GEORGE W. JACQUES, OF STRATFORD, CONNECTICUT, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENER-FEEDING MECHANISM.

Application filed July 14, 1919. Serial No. 310,858.

To all whom it may concern:

Be it known that I, GEORGE W. JACQUES, a citizen of the United States, residing at Stratford, in the county of Fairfield and State of Connecticut, have invented certain new and useful Improvements in Fastener-Feeding Mechanisms, of which the following is a specification, reference being had therein to the accompanying drawings.

10 This invention relates to fastener-supplying means for machines designed to insert fasteners, and is illustrated in a form well suited to the requirements of fastener-inserting machines of the duplex type.

15 An object of the invention is to provide improved means for supplying lacing-hooks to one or more raceways. In so far as the duplex aspect of the invention is concerned a feature consists in an organization comprising a hopper having a discharge opening, duplex raceways arranged to receive lacing-hooks from said opening, and controlling means arranged to position the lacing-hooks flowing from the hopper to the 20 raceways so that all the hooks supplied to one of the raceways will stand in one predetermined position, and all those supplied to the other raceway will stand in a position opposed to that first specified. The 25 invention is not, however, limited to the duplex organization. For example, it provides for an organization comprising a hopper having a discharge opening, a plurality (two or more) of raceways arranged to receive lacing-hooks flowing through said opening, and means arranged to position the lacing hooks in said opening to insure uniformity of position as to the lacing hooks supplied to each of the raceways and to reject all hooks not so positioned.

30 Nor is the invention limited to a plurality of raceways. For example, a feature consists in an organization comprising a hopper formed and arranged to discharge a stream of lacing-hooks, one or more raceways arranged to receive the lacing-hooks, and improved means arranged to control the lacing-hooks as they are about to be received by the raceway or raceways to insure a rate of supply sufficient to satisfy maximum needs of a hook-setting machine.

35 Another feature of the invention consists in a hopper and one or more raceways arranged in such relation that the lacing-

hooks flowing from one to the other will 55 approach the raceway or raceways transversely of their length, and in means forming a series of gateways leading to each raceway to separate from contact with each other the lacing-hooks about to mount the 60 raceway or raceways. The invention also provides improved means for deflecting improperly positioned lacing-hooks from the hooks that are about to mount the raceway or raceways, to avoid congestion in the 65 discharge opening of the hopper and to expedite the passage of the properly positioned hooks to the raceways and the return of the improperly positioned hooks to the hopper.

70 The illustrated construction includes a hopper and an agitator that have already been found advantageous in eyelet-feeding mechanism, the interchangeability of these and other parts in both eyelet-feeding and hook-feeding mechanisms providing for a considerable saving in the cost of manufacturing both kinds by reducing the number of different parts required.

75 Other objects and advantageous details 80 of construction will appear from a more complete description of one embodiment of the invention shown in the accompanying drawings in which,—

85 Fig. 1 is a cross section through a portion of the hopper and the discharge regulating mechanism;

90 Fig. 2 is an elevation of a portion of the feeding mechanism partly broken away; and

95 Fig. 3 is an elevation of the regulating mechanism.

The hopper and fastener agitating mechanisms are substantially identical with those disclosed in United States Letters Patent 1,434,704 granted November 7, 1922, on my application, entitled Fastener feed mechanism, and consists of an inclined stationary hopper 1 having therein a fastener agitator comprising a rotary drum 2 driven from any suitable source and carrying agitating brushes 3 and an upwardly dished baffle plate 4. As shown plate 4 may be thickened at its outer edge, if desired, so that it will be too thick to pass under the 100 beaks of the lacing hooks, thus preventing the lodgment of any thereon. At 105 the base 6 of the hopper is depressed and ex-

tends outwardly beneath the discharge opening 7 in the hopper. The detachable member 8 for controlling the discharge of hooks is arranged in the discharge opening 7 and is curved to conform to the curvature of the hopper. This member comprises a body portion 11, a fin 12 extending inwardly therefrom, and two series of spaced gate members 13 formed on said fin, those of one series being formed on the upper side of the fin and those of the other series on the lower side. These gate members are spaced one from another to provide radial passageways 15 for the shanks of the hooks, and they are also spaced from the body portion 11 to provide channels 14, 14^a for said shanks. The gate members are triangular in cross-section, this shape having been found to be the most effective to separate the properly positioned hooks from those improperly positioned and the most effective to avoid congestion of the hooks at the gateways.

Raceway strips 16 and 17 are fastened to the top and bottom, respectively, of the body portion 11 and their lower ends register respectively with the raceways 9 and 10. The member 8 controls the discharge of hooks so that the only hooks incapable of entering the upper series are those whose shanks extend downwardly, while the only ones capable of entering the lower series are those whose shanks extend upwardly, as shown by Fig. 1. As the hooks pass through the gateways 15, 15 they become lodged on the raceway strips 16 and 17, and then slide on the latter to the raceways 9 and 10. The detachable member 8 also carries a cover strip or guard 18 arranged to overlie the heads of the hooks in the upper series and to close the space formed by the discharge opening 7.

The above described structure for controlling the discharge of hooks is detachably fastened to the hopper by brackets 19 and 20 and wing bolts 22, the latter being screwed into the base portion 5 of the hopper and the brackets being formed with notches so that they may be quickly attached to the hopper and adjusted to register the lower ends of the strips 16 and 17 with the raceways 9 and 10. The lower end of the member 8 is flared as indicated at 21 in Fig. 3, to deflect the improperly positioned hooks toward the center of the hopper.

The operation of the mechanism is as follows. Hooks supported on plate 4, on rotation thereof, find their way over the edge and drop within the path of the agitating brushes 3 and are moved by them past the discharge opening 7 of the hopper. Hooks which become suitably positioned are then gently urged through the slots 15 and into one or the other of the

channels 14, 14^a, the fins 16 or 17 entering the throat beneath the beak of each hook and insuring the arrangement of the throats of the hooks in proper relation by the time they are entirely within the slots 15. The shanks of the fasteners in the upper channel 14 project downwardly while those of the fasteners in the lower channel 14^a project upwardly, while the throats of both series of fasteners extend in the same direction. The fasteners being thus reversely positioned are free to pass out of the hopper and down their respective raceways to the setting mechanism. Fasteners which are not so positioned are moved by the brushes 3 around toward the deflector member 21 and by it are deflected from the discharge opening 7 into the body of the hopper.

Having thus described one embodiment of the invention though it is evident that changes might be made therein without departing from its spirit and scope, and that certain features therein are in no way limited to use of lacing hook setting machine, but might be embodied to advantage with other types of machines, what is claimed is,—

1. In a lacing hook supplying mechanism, a hopper having a discharge opening, means for discharging two series of lacing hooks from said opening, the hooks of the respective series being discharged in reversed positions, and separate raceways for the respective series leading from said opening.

2. In a lacing-hook supplying mechanism, a hopper formed and arranged to discharge a stream of lacing-hooks, a plurality of raceways arranged to receive the hooks from said stream, and means arranged to segregate incorrectly positioned hooks from the correctly positioned hooks about to become lodged on or in the raceways.

3. In a lacing-hook supplying mechanism, a hopper formed and arranged to discharge a stream of lacing-hooks, a plurality of raceways arranged to receive hooks from said stream, and means arranged to divide said stream into a plurality of streams, one for each of said raceways, as the hooks are about to become lodged on or in the raceways.

4. In combination in a lacing-hook supplying mechanism, a hook receptacle having a single discharge opening therein, and assorting means cooperating with said discharge opening for insuring the passage therethrough of two independent reversely arranged series of lacing hooks in different distinct lines.

5. In a lacing hook supplying mechanism, a hopper having a discharge opening, and assorting means for insuring the discharge of two series of lacing hooks from said opening, the hooks of the respective series being discharged in reversed posi-

tions, and the throats of all hooks of a series extending in the same direction.

6. In a lacing hook supplying mechanism, a hopper having a discharge opening, and assorting means for insuring the discharge of two series of lacing hooks from said opening, the hooks of the respective series being discharged in reversed positions, and the throats of all the hooks of both series extending in the same direction.

7. In combination in a hook supplying device, a receptacle for hooks having a discharge opening therein, and a gate for said discharge opening, said gate comprising a member of a shape substantially to conform to said opening and provided with a pair of grooves at its opposite edges, said grooves being of such form as to permit the passage of a pair of reversely positioned hooks.

8. A hook supplying device comprising a receptacle for hooks, and means for regulating the discharge of hooks therefrom comprising a supporting plate provided with a central fin, a gate carried thereby and spaced from the supporting member to form channels therebetween, and a series of grooves in said gate leading into said channels, said grooves being of such shape as to cause the discharge of reversely arranged series of hooks through said gate and into said channels.

9. A hook supplying device comprising a receptacle for hooks, and means for regulating the discharge of hooks therefrom comprising a supporting plate provided with a central fin, a gate carried thereby and spaced from the supporting member to form channels therebetween, and means for determining the direction in which the hooks face at their discharge.

10. A lacing hook supplying device comprising a receptacle for hooks and means for regulating the discharge of hooks therefrom, said means comprising a supporting plate provided with a central fin, a gate carried thereby and spaced from said supporting member to form channels therebetween, a series of grooves leading into said channels, said grooves being of such shape as to cause the discharge of reversely arranged series of hooks through said gate and into said channels and a fin adjacent each channel arranged to take under the beaks of the hooks therein whereby all the hooks entering each channel face in the same relative position therein.

11. A fastener supplying device comprising a receptacle for fasteners having a discharge opening, and means for regulating the discharge of fasteners therefrom, said means comprising a supporting plate provided with a central fin, a gate carried thereby and spaced from the supporting member to form channels therebetween, and

a deflector carried by said fin adjacent the discharge opening to deflect away from said channels all fasteners not properly positioned to pass along within said channels

12. A fastener supplying device comprising a receptacle for fasteners having a discharge opening, and means for regulating the discharge of fasteners therefrom, said means comprising a supporting member provided with a central fin, a gate carried thereby and spaced from the supporting member to form a plurality of channels therebetween for a plurality of series of fasteners and a deflector rigidly carried by said fin adjacent said discharge opening and arranged to deflect from said opening all fasteners not properly positioned within some one of said channels.

13. A fastener supplying device comprising a receptacle for fasteners having a discharge opening, and means for regulating the discharge of fasteners therefrom, said means comprising a supporting plate provided with a fin, a gate carried thereby and spaced from the supporting member to form a channel therebetween, and a deflector carried by said fin adjacent the discharge opening to deflect away from said channel all fasteners not properly positioned to pass along within said channel.

14. In a lacing hook separating mechanism, a hook receptacle having a discharge opening, and means for discharging hooks therefrom through said discharge opening in a plurality of superposed series.

15. In a lacing hook separating mechanism, a hook receptacle, an agitator in said receptacle, and assorting means at the mouth of said discharge opening for insuring the discharge from said receptacle by said agitator of a plurality of independent series of hooks.

16. In a lacing hook separating mechanism, a hook receptacle having a mouth to discharge a stream of hooks, means arranged in said mouth to divide said stream into a plurality of smaller streams at the discharging locality, and a plurality of raceways, one for each of said smaller streams, arranged to receive the hooks adjacent to said dividing means.

17. In a lacing-hook supplying mechanism, a hopper formed and arranged to discharge a stream of lacing-hooks, duplex raceways arranged respectively to receive hooks in different predetermined positions only, and means arranged adjacent to the receiving portions of said raceways to divide said stream into two smaller streams, one for each of said raceways, and to deflect such of the hooks of either stream as are in other than the proper predetermined position to be received in the raceway fed by that stream.

18. In a lacing-hook supplying mecha-

- nism, a hopper formed and arranged to discharge a stream of lacing-hooks, a plurality of raceways arranged to receive the hooks from said stream, and means arranged to divide said stream into a plurality of streams, one for each of said raceways, as the hooks are about to pass out of the hopper and to arrest such hooks as are not correctly positioned to become received in the raceways.
19. An apparatus for supplying lacing hooks, comprising a hopper having a single mouth to discharge a plurality of courses of lacing hooks, a plurality of raceway strips arranged adjacent to said mouth each to receive a course of lacing hooks, and means arranged in said mouth to reject improperly positioned lacing hooks approaching the raceway strips and to accept those properly positioned and guide them to positions astride said strips.
20. An apparatus for supplying lacing hooks, comprising a hopper having a dis-
- charge opening, duplex raceways arranged to receive lacing-hooks from said opening, and controlling means arranged to position 25 the hooks flowing from the hopper to the raceways so that all the hooks supplied to one of the raceways will stand in one predetermined position and all those supplied to the other raceway will stand in a position 30 opposed to that first specified.
21. An apparatus for supplying lacing hooks, comprising a hopper having a discharge opening, a plurality of raceways 35 arranged to receive lacing-hooks flowing through said opening, and means arranged to position the hooks in said opening to insure uniformity of position as to the hooks supplied to each of the raceways and to reject all hooks not so positioned. 40

In testimony whereof, I have signed my name to this specification.

GEORGE W. JACQUES.
